UNITED STATES PATENT OFFICE.

LUTHER F. COLE, OF SACRAMENTO, CALIFORNIA, ASSIGNOR OF ONE-HALF TO EARL H. COCHELL, OF SACRAMENTO, CALIFORNIA.

LOCKING MEANS FOR INCANDESCENT LAMPS

1,314,388.

Specification of Letters Patent. Patented Aug. 26, 1919.

Application filed June 24, 1918. Serial No. 241,606.

To all whom it may concern:

Be it known that I, LUTHER F. COLE, a citizen of the United States, and a resident of Sacramento, in the county of Sacramento and State of California, have invented certain new and useful Improvements in Locking Means for Incandescent Lamps, of which the following is a specification.

This invention relates to improvements in electric incandescent lamps, and an object of the invention is to provide a lamp and socket structure which are arranged whereby the base of the lamp bulb may be easily inserted into the socket, but when once inserted it cannot be removed without destroying one of the contacts of the lamp and thereby rendering the same unfit for further use.

More specifically, the invention comprehends the provision of an ordinary incandescent lamp which has a frangible tongue formed upon and extending outwardly from the central contact at the base thereof which tongue engages in a notch formed in a suitable contact and locking arm carried within the socket, and locks the bulb connected to the socket, requiring the breaking of the frangible tongue before the bulb can be removed.

Other objects of the invention will appear in the following detailed description, taken in connection with the accompanying drawing, forming a part of this specification, and in which drawing:

Figure 1 is a side elevation, showing parts in section of the bulb and socket connected.

Fig. 2 is a fragmentary side elevation showing parts in section of the bulb and socket connected and taken at right angles to Fig. 1.

Fig. 3 is a horizontal section on the line 3-3 of Fig. 1.

Fig. 4 is a detail perspective of the contact and locking arm, and

Fig. 5 is a fragmentary view of a modified form of the base of an incandescent lamp bulb.

Referring more particularly to the drawing, 1 designates the socket member as an entirety, while the bulb is indicated by the numeral 2. The bulb 2 may be of the ordinary construction of electric incandescent lamp bulbs, comprising the base plug 3 which is inserted in the contact shell 4 of the socket 1. The brass or metal shell sur-

rounding the base or plug 3, contacting with the brass shell 4 forms one contact for the circuit through the lamp bulb and the other contact is formed through the engagement between a frangible tongue 5 formed upon the base contact 6 of the lamp bulb and a contact and locking arm 7 carried by the socket member 1.

The contact and locking arm 7 is seated in the ordinary recess 8 formed in the insulating or porcelain plug 9 of the socket member and it comprises a horizontal attaching portion 10 which is attached to the porcelain plug 9, an angular portion 11 and a depending arm 12 upon the lower end of which is formed an arcuate transversely extending projection 13. The inclined contact portion 11 adjustably carries a binding screw 14 by means of which one of the circuit conducting wires which convey the current to the lamp bulb is connected to the contact and locking arm structure 7.

The arcuate transversely extending projection 13 which is formed at the lower end of the depending arm 12 has a notch 15 formed therein which is equal in length or slightly greater than the width of the frangible tongue 5. The socket or notch 15 receives the frangible tongue 5 when the plug or base 3 of the bulb 2 is entirely inserted within the socket member. The upper surface of the outer end of the projection 13 is convexly curved and leads, from the point 16 upwardly to the outer end of the notch 15 in a gradual incline so as to engage and guide the tongue 5 into the notch 15 during the inserting of the plug 3 in the socket 1. The plug 3 is provided with the usual corrugation spirally formed for forming a threaded connection with the shell 4. The tongue 5 has sufficient resiliency to cause it to spring into the notch 15 and thus lock the bulb and socket, preventing the removal of the plug or base 3 of the bulb from the socket without first breaking the tongue 5. When the tongue 5 is broken, it will, naturally destroy the contacts, and render the bulb 2 useless. If it is so desired, the tongue 5 may be made of such material, that in rotating the bulb 2 to remove it from the socket, the tongue will, by engaging against the arm 12 twist the central base contact 6 off the bulb, thus completely destroying the utility of the bulb and preventing its use with ordinary lamp

sockets. The circuit is closed through the lamp bulb 2, in the ordinary manner by the operation of the switch button 18.

In Fig. 5 of the drawing, the tongue 5^a is shown as formed separately from the central base contact 6^a and it may be attached thereto in any suitable manner, such as soldering as indicated at 7^a.

From the foregoing description, and the drawing, it will be apparent that an incandescent electric lamp bulb and socket has been provided, which will form a firm and positive contact between the central base contact of the lamp bulb and its companion contact of the socket, as well as securely lock the lamp bulb connected to the socket, in such manner as to render the bulb useless, after it has been removed from connection with the socket, thereby eliminating the liability of theft of the bulb.

Having thus fully described the invention, what is claimed is:

1. The combination with an incandescent lamp and socket therefor, of means for locking the lamp and socket in connected relation comprising a contact and locking arm carried in the socket, and a frangible tongue carried by the base of the lamp and engaged by said arm to hold said lamp against rotation with respect to the socket.

2. The combination with an electric incandescent lamp and socket therefor, of means for locking the lamp and socket in connected relation comprising a contact and locking arm carried in the socket, and a frangible tongue formed upon the central base contact of the lamp and engaged by said contact and locking arm to form an electrical connection between the bulb and arm and to hold the lamp against rotation with respect to the socket.

3. The combination with an electric incandescent lamp and socket therefor, of means for locking the lamp and socket in connected relation comprising a contact and locking arm carried in the socket, said arm including an attaching portion, an inclined contact portion, a binding screw carried by said inclined portion, and a depending arm extending downwardly from the lower edge of the inclined portion, and a transversely extending arcuate projection formed upon the lower end of said arm and provided with a socket in its upper edge, the upper edge of said projection inclining upwardly toward said socket, and a tongue carried by the base of the lamp and adapted to be engaged in said projection carried socket to lock the lamp against rotation with respect to the socket.

4. The combination with an electric incandescent lamp and socket therefor, of

means for locking the lamp and socket in connection relation comprising a contact and locking arm carried in the socket, said arm including an attaching portion, an inclined contact portion, a binding screw carried by said inclined portion, and a depending arm extending downwardly from the lower edge of the inclined portion, and a transversely extending arcuate projection formed upon the lower end of said arm and provided with a socket in its upper edge, the upper edge of said projection inclining upwardly toward said socket, and a tongue carried by the base of the lamp and adapted to be engaged in said projection carried socket to lock the lamp against rotation with respect to the socket, said tongue being connected to the central base contact of the lamp for forming an electrical connection between the lamp and contact and locking arm.

5. The combination with an electric incandescent lamp and socket therefor, of means for locking the lamp and socket in connected relation comprising an arm carried by the socket, a transversely extending projection formed upon the lower end of said arm and provided with a notch in its upper surface, a tongue carried by the lamp and adapted to be engaged in said notch to lock the lamp against rotation with respect to the socket.

6. The combination with an electric incandescent lamp and socket therefor, of a contact and locking arm carried by the socket and provided with a notch, a spring contact tongue carried by the bulb and adapted to seating in said notch whereby the contact arm will be broken from the bulb upon disconnection of the bulb and socket.

7. The combination with an electric incandescent lamp and socket therefor, of a contact and locking arm carried by said socket, a transverse projection formed upon said arm and provided with a notch, said projection having an inclined head formed therein leading to said notch, a spring contact tongue carried by the bulb and adapted for seating in said notch, whereby the contact tongue will be broken from the bulb upon disconnection of the bulb and socket.

8. The combination with an electric incandescent lamp and socket therefor, of a means for locking the lamp and socket in connected relation, comprising a socket carried receiving member and a spring contact tongue carried by the bulb and adapted for seating in said receiving member whereby the contact tongue will be broken from the bulb upon disconnection of the bulb and socket.

LUTHER F. COLE.
